BIT WITH DETACHABLE BLADE

Harry C. Wilson, Sherman Oaks, Calif., assignor
to Robert H. Clark, Los Angeles, Calif.

Application December 11, 1946, Serial No. 715,423

6 Claims. (Cl. 145—126)

1

This invention has to do with a bit with a detachable blade and it is a general object of the invention to provide a bit having a releasably fastening means that acts to dependably secure the cutting blade in place on the shank of the tool.

The bit of the present invention is of the detachable blade type such as is disclosed and claimed in my copending application entitled "Bit with Interchangeable Blades," Serial No. 715,424, filed December 11, 1946. My present invention is concerned primarily with the mounting of the cutter head on the shank and with the provision of a particularly effective means for securing the head in place on the shank.

It is a general object of my present invention to provide a positive driving engagement between the shank and head which engagement does not permit of any shifting or slipping of the head relative to the shank.

Another object of the present invention is to provide a fastening means for securing a cutting head on a shank, which means is not subject to wedging so tight or to becoming so set as to make it difficult to dislodge the head from the shank.

A further object of the present invention is to provide a retaining or fastening means for a cutter head which operates when the head is in active position on the head carrier, which means involves a part projecting from the carrier to engage in a socket or recess provided for its reception in the cutter head.

Fig. 1 is a side view of a bit embodying the present invention showing it in the course of being used to bore a hole through an object. Fig. 2 is an enlarged view of the structure taken as indicated by line 2—2 on Fig. 1. Fig. 3 is a vertical sectional view taken substantially as indicated by line 3—3 on Fig. 2 with certain of the central parts broken away. Fig. 4 is an end view of the structure, being a view taken as indicated by line 4—4 on Fig. 3. Fig. 5 is an enlarged side elevation of the cutter head showing it detached from the shank and showing it in the position in which it appears in Fig. 1 of the drawings. Fig. 6 is a view similar to Fig. 3 showing a different form of the retaining means. Fig. 7 is an end view of the structure shown in Fig. 6, being a view taken as indicated by line 7—7 on Fig. 6, and Fig. 8 is a detailed view taken substantially as indicated by line 8—8 on Fig. 6.

The tool of the present invention involves, generally, three principal elements, namely a shank element A, a cutter head B, and a retain-

2

ing means C acting to releasably retain the cutter head in operating position on the shank element. The shank element A involves, generally, an elongate shank 10, a head carrier 11 at the outer or lower end of the shank, and a feed screw 12 projecting beyond or from the head carrier 11.

The shank 10 may be of any desired size, shape or length. However, ordinarily it is preferred that it be a simple elongate bar or shaft, uniform in size throughout its length except possibly at its upper end where it is provided with a polygonal part 14 suitable for engagement by a suitable operating device or tool.

15 The carrier 11 provided to carry or support the cutter head B is preferably an integral continuation of the shank 10, and in accordance with my invention I provide a driving engagement between the carrier 11 and the head B by making the carrier non-circular in cross section and by providing an opening through the head to receive the carrier, which opening corresponds in size and shape to the carrier. In the preferred form of the invention the carrier 11 is 20 provided with one or more flat sides 15 and in the form of the invention shown in Figs. 1 to 5, inclusive, the carrier is polygonal in cross section, in fact, it is square in cross section so that it has four equal sides 15. I prefer to flatten or otherwise form the sides 15 of the carrier 11 so that the carrier is somewhat smaller in cross section than the shank 10, leaving a downwardly facing shoulder 16 at the lower end of the shank against which the cutter head B abuts when in 25 place on the carrier.

In Figs. 6, 7 and 8 I show a carrier 11^a somewhat different in form than that just described, in that the carrier is simply a continuation of the round shank 10, except that it has diametrically opposite flattened sides 15^a.

30 The feed screw 12 projects downwardly from or beyond the head carrier 11 and it is preferably a tapered screw having a thread of such character as to properly bite into the material being drilled in order to act as a feed for the tool. The screw is preferably an integral continuation of the carrier. In fact, as shown in the drawings, the shank 10, carrier 11 and screw 12 are formed of one body or length of material.

35 The head B is a disc-shaped element carried by or on the carrier 11. The head has a rim or peripheral surface 20 concentric with the axis of the shank 10, and in the form illustrated it has a downwardly deflected lip 21 provided with 40 a forward cutting edge 22, that is, with an edge

which faces in the direction in which the tool is rotated during operation. The head also has a depending spur 23 with a sharpened edge 24 which spur serves to make an annular cut in the material drilled so that the hole is defined ahead of the edge 22 leaving the edge to merely shave the top from a boss-like projection 25 formed by the spur. The head shown in the drawings is also provided with a clearance opening or throat 26 immediately forward of the lip 21 so that chips established or formed by the cutting edge freely pass the head and do not clog the tool. In the particular case illustrated the edge 22 and the clearance throat adjacent it extend from a point at or near the carrier 11 of the shank element 15 to the periphery 20 of the cutter head.

The central opening 30 provided in the cutter head B to receive the carrier 11 not only fits or corresponds in shape to the carrier 11 but it is centrally located in the disc-like head and is 20 pitched or inclined so that when the head is on the carrier it is pitched or inclined from a plane normal to the longitudinal axis of the tool. The spur 23 depends from the lowermost part of the head, as clearly shown throughout the drawings.

The means that I provide for retaining the head on the carrier involves, broadly, a coupling member carried by one of the connected parts to engage in a socket or recess of the other of the parts. In the preferred arrangement the coupling member is carried by the shank element and engages a socket or recess in the head B. In the form of the invention illustrated in Figs. 1 to 5, inclusive, the coupling member is in the nature of a screw 40 carried by the shank element to be operated so that it extends into a socket or recess 41 in the wall of the opening 30 in the head B. The screw 40 is threaded in an opening 42 which extends diametrically through the shank element and which is inclined or pitched so that one end opens at the carrier 11 while the other end opens at a point at the side of the shank 10 above the carrier 11.

The screw 40 has an outer end accessible at the exterior of the structure which outer end is 45 preferably finished or formed to receive a suitable operating tool. In the case illustrated I have shown a slot 44 in the outer end of the screw suitable for reception of a screw driver or the like. The inner end 45 of the screw which occurs at the carrier 11 is pointed or beveled and the socket 41 in the head which receives the end 45 of the screw is correspondingly pitched so that the end of the screw seats effectively in the socket 41, as clearly shown in Fig. 3 of the drawings.

When the screw 40 is in the operating or advanced position shown in the drawings the pointed end 45 thereof extends into the recess 41 positively holding the head B on the carrier 11 with the head in engagement with the shoulder 16 at the end of the shank 10. To release the head B it is merely necessary to rotate the screw so that the end 45 is withdrawn from the recess 41, whereupon the head can be freely slid from the carrier 11.

In the form of the invention illustrated in Figs. 6, 7 and 8 of the drawings the coupling member is in the nature of a detent preferably a ball 40^a carried in an opening 42^a in the shank element of the tool. The ball 40^a normally projects from the carrier 11^a to enter a socket 41^a provided in the opening 30^a formed through the head to receive the carrier. The opening 42^a in the shank element is preferably a socket of 75

suitable depth to properly accommodate a spring 50 that acts to normally yieldingly urge the ball 40^a outwardly. It will be understood that the mouth of the socket may be slightly contracted or peened over to retain the ball against displacement from the socket, yet allowing it to project enough to enter the recess 41^a as shown in Fig. 6 of the drawings. This particular form of coupling means possesses certain advantages over that first described. For example it does not require any manipulation upon the part of the operator since the ball snaps into and out of operating position as the cutter head is forced onto or from the carrier of the shank element.

From the foregoing description it will be apparent that I have provided a mounting for a cutter head wherein the head is positively driven from the shank element independently of the means employed to retain the head on the shank element. Consequently, the retaining means is not subject to excessive strains and need only be sufficiently heavy or sturdy to hold the head on the carrier portion of the shank. In the form of the invention first described the screw 40 is, in effect, a locking element requiring definite manipulation by the operator before the head can be released, whereas the form last described is a yielding means permitting the head to be withdrawn whenever sufficient withdrawing force is applied.

Having described only typical preferred forms and applications of my invention, I do not wish to be limited or restricted to the specific details herein set forth, but wish to reserve to myself any variations or modifications that may appear to those skilled in the art and fall within the scope of the following claims.

Having described my invention, I claim:

1. A bit of the character described including, a cutter head with a cutting edge, a shank element having an elongate shank and a head carrier on the shank fitting an opening in the head to establish driving engagement between the shank element and head, and means releasably retaining the head on the carrier including a screw carried by the shank element extending into a socket in the head, the screw being threaded in an inclined opening in the shank element so one end opens at the head carrier while the other opens above the head carrier.

2. A bit of the character described including, a substantially flat cutter head with a cutting edge, a shank element having an elongate shank and a head carrier on the end of the shank fitting an opening in the head to establish driving engagement between the shank element and head, the axis of the opening in the head being inclined relative to a line perpendicular to the plane of the head, and means releasably retaining the head on the carrier including a member carried by the shank element shiftable relative to the shank and extending into a socket in the head the periphery of the head being concentric with the shank.

3. A bit of the character described including, a substantially flat cutter head with a cutting edge, a shank element having an elongate shank and a flat sided head carrier on the end of the shank fitting an opening in the head to establish driving engagement between the shank element and head, the axis of the opening in the head being inclined relative to a line perpendicular to the plane of the head, and the shank element having an inclined shoulder engaged by the head when the head is on the carrier, and

means releasably retaining the head on the carrier the periphery of the head being concentric with the shank.

4. A bit of the character described including, a flat cutter head with a cutting edge, an elongate shank with a head carrying portion at one end having driving engagement with the head by engaging in a polygonal inclined opening in the head, and a spring pressed detent member carried by the shank engaging a recess in the head to releasably hold the head on said portion.

5. A bit of the character described including, a substantially flat cutter head having a cutting edge and a central inclined opening, a shank element including an elongate shank, a flat sided cutter head carrier at the outer end of the shank and engaged in said opening to have driving engagement with the head and a feed screw projecting from the carrier, and a member threaded in a transverse inclined opening in the shank element and extending into a socket in the head to releasably retain the head on the carrier.

6. A bit of the character described including, a substantially flat cutter head having a central inclined polygonal opening and a cutting edge, a shank element including an elongate shank, a polygonal head carrier at the outer end of the

shank and engaged in the said opening to have driving engagement with the head, an inclined shoulder on the shank element supporting the head inclined relative to the shank and a feed screw projecting from the carrier, and a screw member carried in an inclined transverse opening in the shank element and extending into a socket in the head to releasably retain the head on the carrier the screw member being accessible at the portion of the head that extends downwardly from the shank, and the periphery of the head being concentric with the shank and having a depending spur at its lowermost part.

HARRY C. WILSON.
